UNITED STATES PATENT OFFICE.

WILLIAM SAKLAD, OF DORCHESTER, MASSACHUSETTS.

SHOE AND ARCH SUPPORTER.

Application filed August 10, 1921. Serial No. 491,249.

To all whom it may concern:

Be it known that I, WILLIAM SAKLAD, a citizen of the United States, and resident of Dorchester, in the county of Suffolk and State of Massachusetts, have invented an Improvement in Shoe and Arch Supporters, of which the following description, in connection with the accompanying drawings, is a specification, like letters on the drawings representing like parts.

My present invention relates to improvements in shoes, and more particularly to an improved and novel arch supporter for use in connection therewith.

Many efforts have been made to provide an arch supporting shoe construction but nearly all of these prior attempts have been with relation to the longitudinal arch of the foot. I have discovered that it is most important to provide arch supporting means for the transverse arch at the ball of the foot to support the metatarsal phalangeal articulations. My invention relates particularly to this portion of the foot and to a novel and improved type of shoe having arch supporting means built into the shoe structure.

The object of my invention, therefore, is to provide a shoe, as an article of manufacture, wherein my novel supporter may be incorporated as an integral part of said shoe. Such shoes, of course, would be made, to special measure to fit each individual requiring the same, and the supporter so positioned in the shoe as to support the correct portion of the shoe affected.

A further object of my invention is an improved method of manufacturing shoes to incorporate therein an arch supporting element.

In the drawings the figure illustrates, in cross section, a shoe made according to my improved method and showing the position of the arch supporting element therein.

Referring to the drawings, 2 designates the supporter which may be formed of metal, leather, leatherboard, fiber, celluloid or any suitable or desirable material. The supporter has a flap or base 3 which extends over the insole of the shoe. The base 3 is preferably of the same material as the supporter itself, although it will be appreciated that this is not an essential element of the invention.

The supporter 2 is illustrated as formed in the shoe during the process of manufacture of the same. As shown, after the upper 6 is lasted with the insole therein, and the welt applied to the shoe, my improved supporter is then applied, with the rim, flange 60 or base 3 extending widthwise of the shoe a sufficient distance so that when the outsole 10 is applied and the outsole stitched to the welt, the outsole stitching will also penetrate and engage the rim of the base 3 and hold the supporter permanently in position. This application of the supporter under the insole, will cause the insole to assume the form of the supporter and produce the same beneficial effect upon the foot of the wearer as if the supporter were temporarily attached.

When a shoe is built according to my invention, no difficult or expensive processes are involved, the several operations of assembling the shoe upper and insole together, pulling over, lasting, inseaming and outsole stitching, sole levelling, laying, edge burnishing and other operations are performed exactly as now generally employed in shoe factories. While I have shown my shoe with the supporter therein as formed in a welt shoe, it will be appreciated that I am not thus limited, but may also build the supporter construction into a McKay shoe.

My invention is further described and defined in the form of claims as follows:

1. As an article of manufacture a shoe, comprising an upper, insole and welt, a supporter for the transverse arch of the foot applied to the shoe between the insole and the outsole, and stitching uniting the outsole, supporter and welt together.

2. The improved process of manufacturing a shoe, which consists in first lasting the upper, insole and component parts, then adding a welt, applying to the bottom of the shoe a supporter for the transverse arch of the foot, then positioning the outsole and stitching the outsole, supporter and welt together with through and through stitching, and then finishing the shoe in the usual manner.

In testimony whereof, I have signed my name to this specification.

WILLIAM SAKLAD.
